UNITED STATES PATENT OFFICE.

LENOX S. ROARK, OF COALINGA, CALIFORNIA.

VENDING APPARATUS.

1,196,586.

Specification of Letters Patent. Patented Aug. 29, 1916.

Application filed March 17, 1916. Serial No. 84,911.

To all whom it may concern:

Be it known that I, LENOX S. ROARK, a citizen of the United States, residing at Coalinga, in the county of Fresno and State of California, have invented new and useful Improvements in Vending Apparatus, of which the following is a specification.

This invention relates to vending apparatus and while particularly designed for dispensing fuel oil such as gasolene, lubricating oil and the like, it will become apparent as the description proceeds that the mechanism hereinafter particularly described is equally well adapted for dispensing any kind of liquid.

The main object of the invention is to provide simple and reliable apparatus whereby upon the depositing of a coin of any denomination, the mechanism will be set so as to deliver a proportionate amount of liquid and the operating mechanism simultaneously released so that the shaft of a pump, for example, will be free to be operated by the person depositing the coin; when the selected quantity of liquid has been pumped, the mechanism will automatically be relocked, rendering it impossible for the pump to be further operated.

A further object of the invention is to provide means whereby the mechanism may be readily adjusted and regulated so as to deliver only the proper amount of liquid in accordance with the prevailing prices of such liquid at the time.

With the above and other objects in view, the invention consists in the novel construction, combination and arrangement of parts, as herein described, illustrated and claimed.

In the accompanying drawings: Figure 1 is a top plan view partly in section showing the vending apparatus of this invention. Fig. 2 is a cross section on the line 2—2 of Fig. 1. Fig. 3 is a cross section on the line 3—3 of Fig. 1. Fig. 4 is a cross section on the line 4—4 of Fig. 1. Fig. 5 is a side elevation of one of the tripping wheels. Fig. 6 is a similar view of another tripping wheel.

The apparatus contemplated in this invention comprises in the preferred embodiment thereof an inclosing case or housing designated generally at A.

1 designates a pump shaft provided at one end with an operating handle 2, said shaft being connected to the pumping apparatus (not shown), which may be of any pre-

ferred construction and designed for pumping gasolene or other fuel oil, lubricating oil or any liquid from a suitable supply source into a receiver which may consist of the tank of an automobile or motor vehicle or any suitable vessel.

Extending at right angles to the shaft 1 is a countershaft or clutch shaft 3 journaled in bearings within the casing or housing A and having mounted on one end thereof a gear 4 having on one side thereof a plurality of concentric gear faces 5, 6 and 7. The wheel 4 is normally loose on the shaft 3, being shown as mounted on the extended hub portion 8 of a ratchet wheel 9 which is fast on the shaft 3 and engaged by a pawl 10 carried by the wheel 4, 11 designating a spring for holding the pawl 10 in engagement with the teeth of the ratchet wheel 9. This enables the wheel 4 to turn freely in relation to the shaft 3 in one direction and to take up the shaft 3 and actuate the same in turn in the opposite direction. Mounted adjustably on the pump shaft 1 is a gear 12 shown in the form of a pinion having a hub 13 and a set 80 screw 14 adapted to engage notches 15 in the shaft 1 for the purpose of enabling the gear pinion 12 to be adjusted longitudinally of the pump shaft 1 so as to engage the desired gear face 5, 6 or 7 of the large gear 4. This provides for a greater or lesser turning movement of the shaft 3 to enable the apparatus to be set for pumping liquid in accordance with the price thereof at the time the machine is in operation.

Mounted fast on the shaft 3 is a locking wheel 16 the periphery of which is notched or toothed as shown at 17 and coöperating with said wheel 16 is a latch bar 18 which extends lengthwise of the casing and is pivotally mounted at one end as shown at 19, the free end portion of the latch bar 18 being movable into and out of engagement with the locking wheel 16 by means to be hereinafter described. Mounted loosely on the shaft 3 at intervals are trip wheels 20, 21 and 22. Any desired number of these wheels may be employed in accordance with the number of coins of different denominations to be used in operating the mechanism. As shown, the wheel 22 is employed in connection with the mechanism to be thrown into operation by depositing a dollar in the vending apparatus, the wheel 21 is used in conjunction with a half dollar deposit and the 110

wheel 20 in conjunction with a dime deposit. Additional wheels may be provided for coins of other denominations.

The mechanism used in conjunction with each of the wheels 21, 22 and 23 is the counterpart of the others and therefore a description of one unit will answer for all. Referring, for example, to the unit comprising the trip wheel 22, it will be observed that said wheel is provided with a female clutch member 23 adapted to coöperate with a male clutch member 24 which is provided with a hub 25 having an annular groove 26 therein to be engaged by the forked end of one arm 27 of a bell crank lever pivotally mounted at 28 within the casing and having another arm 29 which is connected by a pivotal link 30 to a trip lever 31 pivotally mounted at 32 within the casing. The clutch member 24 is feathered to the shaft 3 as shown at 33 causing it to rotate with the shaft but enabling it to slide longitudinally upon said shaft. The clutch member 24 is normally held out of engagement with the clutch member 23 by means of a coiled expansion spring 34 one end of which bears against the base wall 35 of a central bore 36 in the clutch member 24 and the other end of which bears against a collar 37 on the shaft 3. Another larger collar 38 fast on the shaft 3 holds the clutch member 23 and the trip wheel 22 in place. A spacing sleeve 39 is interposed between the inner face of the clutch member 23 and the collar 37 so as to insure disengagement between the clutch members 23 and 24 under the expansive action of the spring 34.

By reference to Fig. 2 it will be observed that the wheel 22 is provided with a single cam projection *a* on the periphery thereof which is adapted to come in contact with the trip lever 31 to impart a slight swinging movement thereto, whereas the tripping wheel 21 is provided with two of such cam projections *b* at diametrically opposite points, and the wheel 20 is provided with ten of such cam projections at *c*. Therefore, the wheel 22 will coöperate with the lever 31 only once in each complete revolution thereof while the wheel 21 will coöperate with its trip lever twice in each revolution thereof and the wheel 20 will coöperate with its trip lever ten times in each revolution thereof. In conjunction with each unit there is employed a coin chute 40 adapted to receive a coin indicated at 41, said coin chute extending downwardly within the casing and projecting above the top thereof as shown in Fig. 2, the coin falling by gravity until it comes in contact with the trip lever 31 where it temporarily rests. In order to operate the trip lever 31 for the purpose of shifting the clutch 24, I provide a hand lever 42 which is shown as pivotally mounted at 43 and the free end portion of

which operates through a slot in the wall of the casing. A lug or projection 44 extends laterally from the lever 43 and works through an arcuate slot 45 in one side of the chute 40. When the lever 42 is depressed until it reaches the bottom end of the slot in the casing, the projection 44 comes in contact with and bears downwardly on the coin 41 thereby imparting a sufficient movement to the trip lever 31 to cause the latter in turn to shift the latch bar 18 out of engagement with the locking wheel 16 thus leaving the shaft 3 free to be turned while the coin is held in the last named position by means of the trip lever 31. The lever 42 is now released and returned to its initial position by means of a spring or its equivalent. The operator now turns the handle 2 and operates the pump shaft 1. This turns the shaft 3 and with it the trip wheel 22, for example, until the cam projection *a* of said wheel comes in contact with the trip lever 31 and pushes the same outward far enough to release the coin 41. The coin then drops into the bottom of the casing and as the cam projection *a* passes beyond the lever 31, the latter moves back to its initial position and throws out the clutch 24. Simultaneously therewith the latch bar 18 is allowed to move back into engagement with the locking wheel 16. The clutch shaft 3 is now locked by means of the wheel 16 and the latch bar 18 and consequently the pump-operating shaft 1 is also locked and remains so until another coin is inserted in the machine. It is, of course, to be understood that there is a coin chute for each trip wheel and also an operating lever for each trip wheel or unit. It is also preferred to place another ratchet wheel 46 on the shaft 3 to be engaged by a detent 47 on the interior of the casing to prevent turning the shaft 3 in a backward direction.

It will, of course, be understood that the gear 4 may be provided with as many concentric gear faces 5, 6 and 7 as may be desired in order to provide for the rise and fall of prices of the liquid being dispensed, it being evident that as the pinion 12 is set nearer the shaft 3, the greater amount of turning movement will be imparted to the shaft 3 and the farther from the shaft 3, the less will be the degree of turning movement imparted to the shaft 3. Until a coin is deposited in the machine, the entire mechanism is locked and the pump-operating shaft cannot be turned. When a coin of any particular denomination is inserted in the machine and the appropriate lever 42 depressed, the mechanism is unlocked and the pump shaft 1 may be given a number of turns proportionate to the amount of gasoline to be pumped in accordance with the denomination of the coin. One or more glass panels or observation openings indi-

cated at 48 are provided to enable the coins to be inspected after they have been deposited in the machine for the purpose of preventing the operation of the machine by 5 slugs when, for any reason, it is suspected that a certain purchaser has been resorting to such fraudulent practice.

Having thus described my invention, I claim:

10 1. In vending apparatus, the combination with a rotary shaft, of a second rotary shaft geared thereto and driven thereby, means for locking the said second shaft, selective means embodying several units each 15 including a trip wheel, means coöperating with the trip wheels for throwing the latter into and out of engagement with said second shaft, and means actuated by the last named means for unlocking said second 20 shaft.

2. In vending apparatus, the combination with a rotary pump shaft, and operating means therefor, of a clutch shaft geared to said pump shaft, a notched locking wheel 25 fast on said clutch shaft, a clutch member feathered to and slidable on the last named shaft, a trip wheel normally loose on the clutch shaft and adapted to be engaged and released by said clutch, a cam projection on 30 said trip wheel, a trip lever resting against said trip wheel and adapted to be shifted by the cam projection thereon and also operatively connected with said clutch for shifting the latter, and a latch bar movable 35 into and out of engagement with said locking wheel and arranged to be tripped by said trip lever.

3. In vending apparatus, the combination with a rotary pump shaft, and operating 40 means therefor, of a clutch shaft substantially at a right angle thereto, a gear on said clutch shaft, pawl and ratchet means connecting said gear and clutch shaft, a gear on said pump shaft meshing with the gear 45 on the clutch shaft, a notched locking wheel fast on said clutch shaft, a clutch member feathered to and slidable on the last named shaft, a trip wheel normally loose on the clutch shaft and adapted to be engaged and 50 released by said clutch, a cam projection on said trip wheel, a trip lever resting against the periphery of said trip wheel and adapted to be shifted by the cam projection thereon and also adapted to shift said

clutch with which it is connected, and a 55 latch bar movable into and out of engagement with said locking wheel and arranged to be tripped by said trip lever.

4. In vending apparatus, the combination with a rotary pump shaft, and operating 60 means therefor, of a clutch shaft substantially at a right angle to said pump shaft, a gear on said clutch shaft, a gear on said pump shaft meshing therewith, a notched locking wheel fast on said clutch shaft, a 65 plurality of clutch members feathered to and slidable on the last named shaft, a plurality of trip wheels normally loose on the clutch shaft and adapted to be engaged and released by the respective clutch members, 70 a cam projection on each trip wheel, trip levers resting against said trip wheels and adapted to be individually shifted by the cam projections thereon and also connected with the respective clutch members to shift 75 the latter, and a latch bar movable into and out of engagement with said locking wheel and arranged to be tripped by any one of said trip levers.

5. In vending apparatus, the combination 80 with a rotary pump shaft and operating means therefor, of a clutch shaft substantially at a right angle thereto, a gear on said clutch shaft provided with a plurality of concentric gear faces, a gear on said pump 85 shaft shiftable longitudinally thereof so as to mesh with any one of said gear faces, a notched locking wheel fast on said clutch shaft, a clutch member feathered to and slidable on the last named shaft, a trip 90 wheel normally loose on the clutch shaft and adapted to be engaged and released by said clutch, a cam projection on said trip wheel, a trip lever resting against the periphery of said trip wheel and adapted to 95 be shifted by the cam projection thereon and also connected with said clutch member to shift the latter, and a latch bar movable into and out of engagement with said locking wheel and arranged to be tripped by said trip lever.

In testimony whereof I affix my signature in presence of two witnesses.
